FLOOR WAXING DEVICE

Edward Matthews, Hamilton, Ontario, Canada

Application March 16, 1932. Serial No. 599,112

2 Claims. (Cl. 91—39)

This invention relates to floor waxing devices of the class wherein the waxing element is reciprocated on the floor to be waxed. It is intended for use with paste wax.

5 One important object of the invention is to generally improve upon waxing devices.

Another important object is to provide a waxing device having a wax fountain and pressure feed.

10 Another important object is to provide a device of the class specified with means for releasing the feed pressure during filling the fountain.

Yet another object is to provide for an even feed.

15 Still another important object is to provide a floor waxing device that, when the wax is exhausted from the fountain, is serviceable as a polisher without alteration or adjustment of the parts.

20 Another object is to provide a device of the kind described which will be simple, durable, efficient, inexpensive to manufacture, and which may be marketed at a competitive price.

With the above and other objects in view as 25 will be hereinafter apparent, the invention consists in general of certain novel details of construction and combinations of parts hereinafter fully described, illustrated in the accompanying drawing and specifically claimed.

30 In the accompanying drawing like characters of reference indicate like parts in the several views, and:

Figure 1 is a top view of a floor waxing device constructed in accordance with this invention; 35 and,

Figure 2 is a cross-sectional side elevation taken on the line 2—2 of Figure 1.

In its present embodiment the floor waxing device comprises the shell 10 opening downwardly, and the pressure shoe 11 slidably mounted in the shell. The pressure shoe is preferably in the form of a plate, the bottom face of which, at least, is even and smooth, and whose area conforms to the inside dimensions of the shell, the 40 walls of which are parallel.

The shell is provided with an outturned peripheral flange 12 at the opening. A feed screen preferably in the form of a cloth 13 (shown in Fig. 2 only) is extended over the opening completely closing it except for the interstices, and the edges of the screen are doubled over the flange 12 and gathered against the lower portion of the shell walls whereafter they are bound preferably by an elastic band 14. Between the 45 screen and the shoe, when the latter is drawn

within the shell away from the opening, is the fountain area for the paste wax. The flange 12 is slightly acclivous towards its outer terminal as a provision for sledding over an uneven floor.

The shoe is provided with a centrally located 60 pair of parallel spaced standards 16 extending through conforming perforations in the shell top. These standards are vertically slotted as at 17, part of the slot extending above and part of it below the shell top in each standard. That portion of the slot extending below the shell top merges with a notch 18 opening on one edge of the standard.

A cam 19 is interposed between the projecting end parts of standards 16 and is provided with 70 opposed axially aligned and eccentrically mounted pintles 20 bearing in the slots 17. The cam bears upon the confronting portion of the shell top and is provided with an operating handle or lever 21.

75 The cam is adapted to make alternately a one-half turn. When the cam is in one extreme position the standards are obviously raised to upper dead center and the shoe 11, which is carried by the standards, is also obviously raised, and when 80 the cam is moved or "thrown" to the other extreme position the standards and shoe are lowered. In the drawing these parts are shown in raised position. When the cam is moved to lower said parts the distance is so calculated as 85 to cause the bottom face of the shoe and the rim of the shell side walls to even.

86 Helical expansion springs 22 urge the shoe downwardly. These springs bear against the shoe and against the inner face of the shell 90 top. Bosses 23 keep these springs in position. When the shoe is flush or even with the shell wall rims the springs are fully relaxed and the cam is in one extreme position.

95 Throwing the cam to the other extreme position raises the shoe under spring urged resistance, but this is quite easily done owing to the long leverage. This extreme position of the cam temporarily locks the shoe in elevated position and removes the influence of the springs. The 100 provision of two or more springs equalizes the pressure on the shoe.

The feed screen 13 first being removed, paste wax may now be spread into the fountain area against the pressure shoe until the level of the 105 wax is flush with the shell wall rims. The device is ready for use when the feed screen is replaced and fixed, and the cam thrown to the position making the springs effective.

110 The release of the springs at once causes the

wax to commence to ooze through the feed screen. Thus the wax is gradually fed to the floor as it is used, and obviously the rate of flow may be predetermined by the use of a feed screen of proper texture.

5 The wax will regularly feed until the filling is exhausted, but if it is intended that the work be discontinued before the fountain area is empty the flow may be stopped by throwing the cam.

10 When the device is thoroughly empty the shoe, as previously specified, is level or even with the shell wall rim, and in this condition, granted that the feed screen is still in position, the device may be used for polishing the previously waxed floor.

15 The notch 18 enables the cam pintles 20 to enter the slots 17 during assembling. This is accomplished by pressing the shoe well beyond normal range into the shell thereby bringing the notch on the outside of the shell.

20 24 are ears mounted on the shell to receive the furcations of a handle (not shown). With the handle removed the device may be used by grasping by the hand, for stairways and the like.

25 There has thus been provided a simple and efficient device of the kind described and for the purpose specified.

It is obvious that minor changes may be made in the form and construction of the invention 30 without departing from the material spirit thereof. It is not, therefore, desired to confine the invention to the exact form herein shown and described, but it is desired to include all such as properly come within the scope claimed.

35 Having thus described the invention, what is claimed as new, is:

1. In a floor waxing device, a shell opening downwardly, a pressure shoe slidably mounted in the shell and having a lower range terminal 40 and a normal upper range terminal, springs

mounted in the shell urging the shoe downwardly toward the orifice of the shell, feed means across the orifice, a pair of parallel spaced standards superimposed on the shoe and extending slidably through individual perforations in the shell top to the outside, a cam interposed between the projecting parts of the standards, oppositely disposed pintles eccentrically mounted on the cam and bearing in vertical slots in the standards, said slots extending above and below the shell top, the cam having camming action against that portion of the shell top bridging the main portions thereof between the perforations therein to vary the position of the standards, the lower ends of the standard slots merging with notches opening on the vertical edges of the standards providing access to the slots for the pintles when the shoe is forced beyond its normal upper range terminal moving the notched portions of the standards to the outside of the shell.

2. In a floor waxing device, a shell opening downwardly, a pressure shoe slidably mounted in the shell, a pair of parallel spaced standards superimposed on the shoe and extending slidably through the shell top to the outside, a cam interposed between the projecting parts of the standards, oppositely disposed pintles eccentrically mounted on the cam and bearing in vertical slots in the standards, said slots extending above and below the shell top, the cam having camming action against the shell top to vary the position of the standards, the lower ends of the standard slots merging with notches opening on the vertical edges of the standards providing access to the slots for the pintles when the shoe is forced beyond its normal upper range terminal moving the notched portions of the standards to the outside of the shell.
